WINDOW CONSTRUCTION

Edmund Peremi and Louis Toth, Manhasset, N. Y.

Application September 29, 1933, Serial No. 691,553
Renewed January 31, 1935

25 Claims. (CL 139—75)

This invention relates to window constructions, and more particularly to casement windows, an object of the invention being to provide a window of this type having an improved construction and shape of hollow bars constituting all four sides of the sash, and co-operating with the frame bars to insure a weather-tight fit when the sashes are closed.

A further object of the invention is to provide a sash of this character in which the metal employed in forming the stiles and rails of the sash may be relatively light and yet will be strong and durable in use.

A further object is to provide improved construction of frame bars and improved arrangement of weather-stripping;

A further object of the invention is to provide a subdivided frame construction whose parts can be used interchangeably, without alteration, for swinging sashes or for fixed window lights or sashes.

A further object is the use of the same frame member throughout and adding a specially designed shape to it; the combination of the two conforming with the combination of jamb and swinging sashes to create a neat, architectural appearance.

A further object is to create a combination of window frame and sash having hinge arrangement close to top and bottom of the hinge stile and having a specially formed clip provided on the sash between the top and bottom hinges for engaging a member of the frame and automatically holding the sash stile tight to the jamb to maintain a weather-tight joint.

A further object is to provide a window construction embodying many novel features of construction and combinations and arrangements of parts, all of which will be more fully hereinafter described and pointed out in the claims.

In the accompanying drawings,—

Figure 1 is a diagrammatic view in elevation illustrating a form of window construction embodying my invention and including a fixed sash A and hinged or casement sashes B and C respectively;

Figure 2 is an enlarged broken view in vertical section on the line 2—2 of Figure 1;

Figure 3 is an enlarged broken view in horizontal section on the staggered line 3—3 of Figure 1;

Figure 3a is a view of a modified form of bar for transom sashes;

Figure 4 is a view similar to Figure 2, illustrating a modification;

Figure 5 is a perspective view in section similar to one end of Figure 4 and illustrating another modification;

Figure 5a is a view in cross section, illustrating another form of bar;

Figure 6 is a view similar to Figure 3 illustrating a modified form of weather-strip; and

Figures 7, 8, 9, and 10 are fragmentary views 10 in vertical section, the lower portion of the sash and frame illustrating other modifications.

The window frame comprises vertical side bars 1, a sill bar 2, an upper or cap bar 3, a transom bar 4 and a mullion bar 5. The transom bar 15 and the mullion bar sub-divide the frame into panels or sections. As shown in Fig. 1, the upper panel is used for a fixed transom A and the two lower panels are used for swinging sashes B and C which open outward. It is a feature of 20 the invention, however, that each of the bars 1, 2, 3, 4 and 5, presents toward each panel bounded by it an outline or configuration identical with the outline or configuration of each of the other members. This configuration is such that any 25 panel may be readily used for the mounting of a swinging sash as B or C or the mounting of a stationary sash or light as A. Each of the bars 1, 2, 3, 4 and 5 is L-shaped, and is provided with short flanges 6 and 7 to form a partially 30 closed pocket 8 in the angle of the L to receive a yielding weather strip 9. The weather strip desirably consists of a strip of felt or other suitable non-metallic material, as illustrated in most of the figures of the drawings, or it may consist of a metal weather strip 10 as shown in Figs. 6 and 9 of the drawings. The weather strip 10 is made of sheet material bent so as to fit within the pocket 8 and provided with a freely movable web or tongue portion 11 which is exposed 35 through the open side of the pocket.

The swinging sashes B and C are of like construction and each is formed to present the same contour externally along all four of its edges. Each sash is composed of hollow or tubular bars 45 12 forming the stiles and the bottom and top rails. The bars 12 are formed of relatively thin metal by extrusion, drawing, or any other suitable process. They are of trapezoidal form, each comprising parallel outer and inner walls 13 and 50 14, the former being longer than the latter, a connecting wall 15 at right angles to the walls 13 and 14, and a connecting wall 16 extending obliquely outward from the shorter wall 14 to the longer wall 13 so that the sash frame at its 55

edges has a bevel. The bevelled wall 16 is formed with an outwardly projecting flange 17 intermediate its sides for engaging the weather strip 9. The wall 14 engages a flange 18 which extends parallel to the plane of the window at the inner side of the window frame. An extension or flange 19 of the wall 13 engages a relatively short flange 19a of the adjacent frame bar which is located at the outer side of the window and in a plane parallel to the plane of the window. Thus there is provided along all the edges of the sash three continuous lines of contact between the sash and the frame, the inner and outer lines of contact being formed by metal to metal engagement of parts and the intermediate line of contact being formed by the flange 17 and weather strip 9. The flange 6 is provided substantially midway of the wide inner flange 18, of the frame, and the flange 7 is provided substantially midway 20 of a transverse flange 18a.

The weather strip pocket defined by the flanges 6 and 7 occupies, therefore, only a minor portion of the angle between the flanges 18 and 18a so that an air space is defined between the wall 25 16 of the tubular bar 12 and the flanges 18 and 18a of the frame. The flange 17 sub-divides this air space into two separate compartments and effectively seals the compartments from one another. Any air which passes the joint formed 30 by the flanges 19 and 19a is retarded in velocity in passing through the space at the outer side of the flange 17 and again any air that passes the flange 17 is retarded in velocity in passing through the space at the inner side of the flange 35 17.

The flange 18 of each frame member has an outward extension 18b beyond the flange 18a to form a T with the latter. The flanges 18a, 18b and 19a form an external channel on each 40 of the frame bars and a reinforcing angle bar 18c of steel or other suitable material is affixed in the base of the channel with its outwardly extending web or flange disposed parallel to the plane of the window and at a short distance inward from the flange 19a. The angle bars 18c are connected end to end to form a rigid reinforcing frame.

At the outer extremity of the flange 19a provision is made of a short transverse flange 19b 50 which is thickened at its outer end so as to provide a wedge-shaped caulking space for the reception and retention of caulking material 19c. The caulking material penetrates into the structure far enough to partially fill the space between the reinforcing member 18c and the flange 55 19a and to partially fill the space between the reinforcing member and the sill or other adjacent building wall element.

The sash bars 12 have integral flanges 20 thereon and the glass panes 21 are held by clips 22 and putty 23, the bars being formed with dovetail recesses 24 for receiving one end of the clip while the other end of the clip bears against the glass. These clips are hidden by the putty. The dovetail groove serves not only as an abutment or retaining recess for the retaining clip, but also as an interlocking recess inside which a portion of the set putty forms a dovetail connection. This feature is advantageous for the reason that putty does not adhere well to metal, especially in the case of bronze or other non-ferrous metal, so that an interlocked joint is desirable.

At the hinges and at any other points where 75 the sash may require reinforcement the bars

12 are strengthened by the insertion of metallic angle bars 25.

The transom and mullion bars 4 and 5 constitute double angle bars with the same arrangement of flanges already described. The double 5 angle bars are connected by an internal web 26 which is provided with a recess for receiving a reinforcing bar 27 of stronger material than that of which the frame proper is constructed. The reinforcing bar 27 is preferably of steel. The 10 reinforcing bar 27 may, if necessary, be extended beyond the face of the transom bar in which it is mounted and it is covered by a cap 28 of non-corrosive metal. The cap 28 is provided with side flanges 29 which are slidably received in opposed 15 grooves 30 formed in the transom bar.

In instances where it is not necessary to use as wide a reinforcing bar as that just described, a bar such as illustrated in the mullion 5 may be employed. In this case the reinforcing bar 26 27 is completely received in the recess and is held in place by means of a plate 31. The plate 31 may be sprung or slid into retaining recesses 30 formed in the mullion bar so that the inner face of the plate 31 is caused to lie flush with the 25 inner plane of the window frame.

The transom bar 4 is desirably provided at the top of the outer side thereof with an outwardly and downwardly projecting curved lip 32 for deflecting water from the upper sash outwardly 30 away from the lower sash to prevent it from running down between the sashes.

The sashes B and C are shown as outwardly swinging sashes in Figs. 1 to 3. Any suitable form of hinge mechanism may be employed but 35 hinges of the type shown and described in United States Letters Patent No. 1,987,516 granted to us on January 8, 1935 are deemed preferable.

Each hinge comprises two members 33 and 34. The member 33 is secured to the frame and the 40 member 34 is secured to the sash. The member 33 has a straight slot 35 therein, and is also provided with a curved slot 36 at an angle to the straight slot. The member 34 has a screw or pin 37 which rides in the straight slot, and a screw or 45 pin 38 which rides in the curved slot 36 so that when the sash is swung open these pins 37 and 38 riding in the respective slots will cause the sash to move in an outwardly direction or away from the frame, as indicated by dot and dash 50 lines in Figure 3. The members 33 of the lower hinge are provided with adjusting screws 39 at their outer ends engaging the sill 40, so as to adjust the hinges and properly support the same and the sash to which they are connected. In 55 order to preserve a tight engagement between the sash stiles and the corresponding vertical frame members throughout the height of the sash between the hinges which are located at or near the top and bottom thereof, interengaging means are 60 preferably provided which become effective when the sashes are swung into closed position. As illustrated in Fig. 3 this may be accomplished by providing the sash stiles with one or more clips "y" which are arranged to interlock or wedge be- 65 hind the flanges 7 of the frame members and the sashes are closed. The engagement between the clips "y" and the flanges 7 holds the sashes firmly in contact with the frame members between the hinges and there is no danger of the sashes 70 springing out of tight sealing engagement with the frame by reason of wind pressure or otherwise.

The transom panel of Figs. 1 and 2 is shown as filled with a stationary pane A. It will be ob- 75

served that the same inside configuration of the frame bars is utilized for co-operating with the pane A as is utilized in the other panels for co-operating with the swinging sashes B and C. 5 When a stationary sash or pane is installed the pockets bounded by the flanges 6 and 7 are used for receiving resilient retaining clips 1a which comprise curved portions imprisoned in the pockets and edge portions for bearing against the pane to hold it firmly against the seat formed by the flange 18. Putty is applied in the angles formed by the frame bars bounding the transom opening and is pressed into the pockets formed by the flanges 6 and 7 to provide a secure interlocking engagement with the frame members. 10

It will be readily apparent that the transom opening is adapted instead to have a hinged transom sash mounted in it while either of the lower panels is adapted, if preferred, to have a stationary sash or pane mounted in it. In fact the construction lends itself to any desired arrangement or combination of fixed and swinging sashes. 15

An object of this window construction is to enable either a fixed panel or a hinged panel to be readily installed in any part of the window as desired without any alteration of the frame. The frame may be bricked in for years when a change becomes necessary. In such a case it is not necessary to remove the frame from the masonry 20 and carry it back to the factory for alterations, but the change can simply be made in the field without removing the frame by applying a new hinge member where a swinging panel is to be substituted, or by removing the hinge member which is present when a stationary panel is to be substituted. 25

As an alternative arrangement for securing a stationary sash in a frame panel, disclosure is made in Fig. 3a of a stationary sash having edge or boundary members adapted to be combined with the frame bars illustrated in Figs. 1 to 3. The sash bars of Fig. 3a are all of identical construction whether used for stiles, top rail or bottom rail. Each bar of the stationary sash comprises an outer flange a provided with a lip f adapted to fit into a recess g of the flange 18a. Each sash bar also includes a transverse web or wall b2 provided with a dovetail groove b1 in its exposed face, a flange e for setting against the flange 18 and a flange e1 forming a pane seat. A screw c is passed through the base of the dovetail groove b1 and threaded into the flange 18a of the frame. Threaded holes for the screws c and grooves g for the lips f are provided in all of the flanges 18a of the frame so that a frame of standard construction is adapted, without alteration, to be used for mounting either a swinging or a stationary sash in any panel thereof. The flanges b and e1 form a glazing angle. Clips 22 are used in conjunction with the dovetail groove b1 for holding the pane 21 in place and putty 23 is applied to cover and conceal the clips. 50

The arrangement of Figure 3a can be applied after a window is installed in a building without removing the sash frame. 55

Figs. 4 and 5 disclose a modified form of construction in which the sashes swing inward instead of outward. In this construction ordinary plate hinges are employed since it is not necessary to space the sashes from the frame for cleaning. 70

In general the principles followed in the construction of Figs. 4 and 5 are the same as those of Figs. 1 to 3 and 3a, all of the frame bars being of identical construction and the arrangement

being such that either a stationary pane or a swinging sash may be mounted in any frame panel. The frame members 83 are secured in the masonry in any approved manner and each is provided with a dovetail groove 68 in its transverse wall. When the panel, of which one of these members forms a boundary, is to receive a swinging sash an additional bar 64 is secured to the bar 83. The bar 64 has an expansible tenon 65 which is forced into the dovetail groove 68 in the member 83. There is also a tenon 67 on the member 63 which is forced into a mortise 68 on the member 64. The member 64 constitutes a wall against which the sash engages, and also forms a pocket for the accommodation of the weather strip 8 to be engaged by a flange 69 on the sash bar 70. When a frame panel of Fig. 4 is to be used for receiving a stationary sash the combination is effected in substantially the same manner in which the pane 21 is associated with a swinging sash of Fig. 2. A spring clip 22 is set with its tail portion abutting one wall of the dovetail groove 68 and with its opposite end bearing against the pane 21. Putty 23 is applied to cover the clips 22, the putty interlocking with the dovetail groove 68. 10

The sash bars 12 are capable of a wide range of modification in their precise shape, and some of these modified shapes will now be described: In the modification illustrated in Figure 7 of 30 the drawings, a sash bar 42 corresponding to the sash bar 12 has a bend or angle 43 in its diagonal member 44, and this bar at its angle 43 engages the weatherstrip 8 and obviates the necessity of providing a flange, such as shown at 17 in the other form. In the modification illustrated in Figure 8 of the drawing a tapering wall or angular bar 45 of the sash bar 46 corresponding to the sash bar 12 has an angular contact portion 47 thereon, engaging the weather-strip 8 which is 35 located in a pocket 48 formed in the angle of the frame bar 49. 40

In the modification illustrated in Figure 9 of the drawings, the frame bar 50 instead of having a diagonal wall has a stepped wall 51 which contacts with webs 52 and 53 on the frame bar 54, and a flange 55 contacts with the outer face of the frame bar. An angle 56 of the wall 51 engages the weather-strip 8, so that in this form of construction there is a four-point contact. In the modification shown in Figure 10 of the drawings, a sash bar 57 has an angular wall 58 engaging a weather-strip 59 in the angle of the frame bar 50, and also engages a flange 61 on the frame bar. A flange 62 in the sash 57 engages the frame bar 50 so that in this form of the invention, as in most forms of the invention, there is a three-point contact between the sash and frame, one of which contacts constitutes a weather-strip. 50

It will be noted that the frame bar throughout the opening is of the same cross-sectional shape in the main figures of the drawings. This leaves an air space and also a space for condensation, and a weep-hole may be provided in the part 64 to allow the moisture to escape. 65

In the modification illustrated in Figure 5a of the drawings, the bars are likewise made of two sections h and i secured by screws j, and the member h has its side flanges provided with grooves k receiving flanges l and m, respectively on the other member. The adapter here shown is designed for use in a structure like that of Fig. 4 so that the weather-strip holding adapter at one side of the transom bar will be matched by a 75

stationary sash adapter at the opposite side to give a balanced appearance.

While we have illustrated what we believe to be the preferred embodiment of our invention, it is to be distinctly understood that various slight changes may be made with regard to the form and arrangement of parts without departing from our invention, and hence we do not limit ourselves to the precise details of the invention but consider ourselves at liberty to make such changes and alterations as fairly fall within the spirit and scope of the claims.

The feature of providing a sash with dovetailed grooves adjacent the glass, in combination with putty keyed in the grooves and clips anchored in the grooves and imbedded in the putty, disclosed but not specifically claimed herein, is claimed in our pending application Serial No. 693,199, filed October 11, 1933 for Window construction.

20 The feature of providing a resilient sheet metal sealing member in a channeled frame bar with one of its legs disposed to intersect at an acute angle the path traversed by the sash in closing, together with a lip on the frame bar to cover and 25 guard the free edge of the weather strip leg when the sash is open, is not specifically claimed herein, but is claimed in our pending application, Serial No. 14,965, filed April 6, 1935 for Windows.

What we claim is:

30 1. A window frame comprising an outer reinforcing portion extending entirely around the window opening, said portion being of angle cross section and having a transverse flange and a flange extending therefrom in a plane parallel to the plane of the window and disposed towards the outside of the window, and a covering of non-corrosive metal attached to said outer portion, said non-corrosive covering having a channel-shaped portion enclosing and concealing the 40 exposed face of the transverse flange of said outer portion and having a flange forming a T-head at the inside of the window and an L-shaped flange at the outside of the window comprising a portion projecting outwardly from the window opening in a plane parallel to the plane of the window and a portion extending to the front of the window transverse to the plane of the window, said L-shaped flange and the outwardly extending flange of said outer reinforcing member providing a caulking pocket.

50 2. A window frame comprising an outer reinforcing portion extending entirely around the window opening, said portion being of angle cross section and having a transverse flange and a flange extending therefrom in a plane parallel to the plane of the window and disposed towards the outside of the window, and a covering of non-corrosive metal attached to said outer reinforcing portion enclosing and concealing the exposed 60 face of the transverse flange thereof, said non-corrosive member having an L-shaped flange at the outside of the window comprising a portion projecting outwardly from the window opening in a plane parallel to the plane of the window and a portion extending to the front of the window transverse to the plane of the window, said last 65 named portion having a beveled or undercut outer surface, said L-shaped flange and outwardly extending flange of said outer reinforcing member providing an undercut caulking pocket.

70 3. A window frame comprising a frame member having an L-shaped flange along its edge at the outside of the window, the outer leg of the L-shaped flange which extends transversely to the plane of the window being thickened towards

its outer or free edge so as to provide an undercut caulking pocket between said flange and a surface of the masonry in which the window frame is set transverse to the plane of the window.

4. A window comprising a frame formed of members surrounding a window opening, each of said members comprising a base portion transverse to the plane of the window and inner and outer flanges, one of said flanges being wider than the other, a swinging sash carried by said frame having portions adapted to engage in sealing contact with said flanges when the sash is closed, there being a marginal air space enclosed between the sash and the flanges and bases of said frame members, means formed on the wider flange and base of said frame members providing a pocket in a corner of the frame formed by the base and the wider flange, a yielding weather strip in said pocket, the said sash being formed to provide a marginal projection between the front and rear faces thereof extending into said marginal air space and adapted to engage in sealing engagement with the yielding weather strip in said weather strip pocket when the sash is closed.

5. In window construction, the combination of a frame and swinging sash, said frame comprising portions having an angular cross section consisting of a base at right angles to the plane of the window, a wide flange at one side of said base having a seat thereon for engagement with the sash, means at the other side of the base providing a second seat for the sash located nearer to said base than the seat provided by said wide flange, said wide flange and base being formed to provide a pocket in the corner between said base and wide flange, a yielding weatherstrip imprisoned in and by said pocket, said sash comprising a portion of angular cross section including a base with glass receiving rabbet thereon and a portion extending at right angles to said base in a plane parallel with the plane of the window, the margin of said angular portion being adapted to engage with the seat on said frame adjacent to the base thereof when the window is closed, the base of said sash member also having a seat at the edge thereof opposite to that carrying said angular portion adapted to engage the seat provided by the margin of the wide flange on the frame, whereby when the window is closed said frame member and said sash member combine to form a substantially rectangular section having a yielding weatherstrip in one corner thereof, said sash member having a sealing projection located between the specified points of engagement between said sash and frame, said projection engaging in sealing contact with said yielding weatherstrip when the sash is closed.

6. In window construction, the combination of a frame and swinging sash, said frame comprising portions having an angular cross section consisting of a base at right angles to the plane of the window, a wide flange at one side of said base having a seat thereon for engagement with the sash, means at the other side of the base providing a second seat for the sash located nearer to said base than the seat provided by said wide flange, said wide flange and base being formed to provide a pocket in the corner between said base and wide flange, a yielding weatherstrip in said pocket, said sash comprising a portion of angular cross section including a base with glass receiving rabbet thereon and a portion extending at right angles to said base in a plane parallel with the

- plane of the window, the margin of said angular portion being adapted to engage with the seat on said frame adjacent to the base thereof when the window is closed, the base of said sash member 5 also carrying a seat at the edge thereof opposite to that carrying said angular portion adapted to engage the seat provided by the margin of the wide flange on the frame, whereby when the window is closed said frame member and said 10 sash member combine to form a substantially rectangular section having a yielding weatherstrip in one corner thereof, said sash having a portion extending substantially diagonally across said rectangular section between the angular portion 15 at one side of said sash and the seat adjacent to the base of the sash, said diagonal portion having a rib near the middle thereof for engaging in sealing contact with said weatherstrip when the sash is closed.
- 20 7. A frame for swinging windows comprising elements having a cross sectional configuration comprising a base at right angles to the plane of the window, an L-shaped flange at the outside of said base, one portion of said L-shaped flange 25 projecting outwardly in a plane parallel with the plane of the window and providing a seat for engagement by a portion of a sash, the second part of said L-shaped flange extending outwardly in a direction substantially at right angles to the plane 30 of the window and being adapted to provide a caulking pocket, the base of said frame member having a flange at the edge thereof toward the inside of the window extending inwardly in a plane parallel with the plane of the window, the 35 inner margin of said flange constituting a sash engaging seat, and webs on said base and last named flange portion of said frame member providing between them a pocket for retaining a weatherstrip.
- 40 8. A window frame comprising members of angular cross section, said members each including a base located at right angles to the plane of the window, said base having a flange located at the edge thereof nearest the outside of the window, extending outwardly therefrom in a plane parallel to the plane of the window, said base also having a flange located at the edge thereof nearest the inside of the window and extending inwardly in a plane parallel to the plane of the 45 window, said base also having a narrow web extending inwardly from the middle part thereof in a plane parallel to the plane of the window, said wide inwardly extending flange at the inside of said base having a narrow web located near the middle portion thereof and extending longitudinally of said frame member, said last named two narrow webs being adapted to constitute a pocket for holding a weatherstrip when said frame is used with a swinging sash, and the marginal portion 50 of said wide flange on the inside of the frame base and the narrow web projecting from the middle portion of said flange being adapted to constitute a glass rabbet when the frame is utilized to hold a fixed pane of glass.
- 55 9. In window frame construction a transom bar or mullion comprising a base portion having flanges extending from opposite sides thereof in a plane parallel to the plane of the window, each side of said base portion and the flange extending 60 therefrom being provided with co-operating webs extending longitudinally thereof and adapted to form a partially closed pocket in the corner between the base portion and flange.
- 65 10. A window frame adapted for use with 65 swinging sashes or with fixed panes of glass said 70 frame including members comprising a base portion and a flange extending inwardly therefrom in a plane parallel to the plane of the window, said base and flange providing spaced seats for engagement with a swinging sash when used, and an adapter member removably attached to said frame member, said adapter member having a base portion spaced from the base of the frame member and a flange projecting inwardly from the base of said adapter member, said flange and 75 base of said adapter member providing a glass receiving rabbet for a fixed pane of glass.
11. A window frame adapted for use with 15 swinging sashes or with fixed panes of glass, said frame including members comprising a base portion and a flange extending inwardly therefrom in a plane parallel to the plane of the window, said base and flange providing spaced seats for engagement with a swinging sash when used, and an adapter member removably attached to said 20 frame member, said adapter member having a base portion spaced from the base of the frame member and a flange projecting inwardly from the base of said adapter member, said flange and 25 base of said adapter member providing a glass receiving rabbet for a fixed pane of glass, said base of said adapter member having a dovetailed groove therein for receiving glass holding clips and putty.
12. An adapter for adapting a window frame 30 constructed to receive a swinging sash to receive fixed panes of glass comprising a member having in cross section a base extending substantially at right angles to the plane of the window, a narrow flange extending outwardly in a plane parallel to 35 the plane of the window from the edge of said base located towards the inside of the window and an outwardly projecting wide flange extending from the edge of said base near the outside of the window, said base also having a flange extending 40 inwardly in a plane parallel to the plane of the window and constituting a glass supporting ledge.
13. A window having a frame comprising members surrounding the window opening and a transom bar or mullion, all the members of said frame being of uniform cross section and said transom bar or mullion having portions at opposite sides thereof of a cross section uniform with the corresponding portions of the frame, a swinging sash mounted in said frame at one side of 45 said transom bar or mullion and having portions adapted to seat against said frame and transom bar or mullion members, and adapter strips removably attached to said frame and transom bar 50 or mullion members at the opposite side of said transom bar or mullion from the location of said swinging sash, said adapter members having parts to hold a fixed pane of glass in the same plane as the pane of glass carried by the sash 55 when said sash is closed.
14. In a window construction, a frame and a sash pivotally supported upon the frame adjacent one side thereof, said frame being formed to provide seats for engagement by corresponding seats 60 on the sash, a yielding weather strip carried by the frame, a projection on the sash adapted to engage said weather strip, and a clip on the side of the sash adjacent to the side of the frame to which said sash is pivoted, said clip being adapted 65 to move into and out of interlocking engagement with a part of the frame when the sash is closed or open, said interlocking engagement acting to hold the pivoted edge of the sash in close sealing 70 75

engagement with the side of the frame to which the sash is pivoted.

15. In a window construction, a frame and a sash pivotally supported upon the frame adjacent one side thereof, said frame being formed to provide seats for engagement by corresponding seats on the sash, a yielding weather strip carried by the frame, a projection on the sash adapted to engage said weather strip, and interlocking formations on the side of the sash adjacent to the side of the frame to which the sash is pivoted and on said side of the frame adapted to move into and out of interlocking engagement when the sash is closed or opened, said interlocking formations serving to draw and hold the side of the sash and the side of the frame to which the same is pivoted in firm sealing engagement when the sash is closed.

16. A window frame comprising members surrounding the window opening and one or more members crossing the window opening to form transom bars or mullions, all of said members having flanges extending in planes parallel to the plane of the window, all of said flanges lying in the same plane and being of substantially the same width, said frame carrying a fixed pane of glass supported on the flanges of the part of the outer frame members at one side of said transom bar or mullion and on one flange of the latter, and a swinging sash hinged at the side of the frame at which the flanges are located, but at the opposite side of said transom bar or mullion from the fixed pane, and engaging the flanges on the frame members and the flange on the transom bar or mullion on said side of the latter, said sash having a glass receiving rabbet therein adapted to support a pane of glass in the same plane as the pane of glass supported directly by the flanges of the frame and transom bar or mullion.

17. A window frame for casement windows comprising members shaped in cross section to provide a broad base having a flange at the edge thereof towards the outside of the window comprising a narrow portion extending outwardly in a direction parallel to the plane of the window, and a portion extending from the margin of said narrow portion in a direction substantially at right angles thereto towards the outside of the window, said base having a T flange at the edge thereof toward the inside of the window, and having a wide shallow dovetailed groove in the exposed face of the base between said flanges.

18. In window construction, the combination of a frame and swinging sash fitted thereto, said frame composed of members each comprising a base portion extending substantially at right angles to the plane of the window, said base portion having an inwardly extending flange parallel to the plane of the window at one side thereof, and having a dovetailed groove in the exposed face thereof, a supplemental member carried by said frame member having a base portion interlocking in said dovetailed groove and having a flange extending from the edge of said base portion nearest the outside of the window, inwardly in a plane parallel to the plane of the window, said supplemental member having a weather strip receiving pocket formed between said base and said flange thereof, said swinging sash member having portions adapted to engage the flange on the base of the outer frame member and the flange on said supplemental member respectively, said sash also having a projection adapted to engage and seal against a weather strip carried in said weather strip pocket.

19. A window comprising a frame having marginal members of similar formation extending around all sides thereof, each of said members comprising in cross section a base having a dovetailed groove in the exposed face thereof and having a flange projecting from the inside edge of the base inwardly in a plane parallel with the plane of the window, said frame carrying a transom bar or mullion comprising a base each side of which is provided with a dovetailed groove corresponding with the dovetailed grooves in the frame members, said transom bar or mullion also having flanges projecting therefrom in the same plane as the flanges projecting from the frame members, supplemental members each comprising a dovetailed base and a flange projecting parallel with the plane of the window, said supplemental members being mounted in the dovetailed grooves in four sides of the window opening at one side of said transom bar or mullion, a pivoted sash mounted to swing in the window opening at said side of said transom bar or mullion, said sash having a flange thereon against which a pane of glass is adapted to seat, said flange being located in the same plane as the flanges upon said frame and transom bar or mullion members and a fixed pane of glass seated against the flanges on the transom bar or mullion and frame members in the window opening at the opposite side of the window opening in which the pivoted sash is mounted, the said fixed pane of glass and the pane of glass in said movable sash being located in the same plane when said sash is closed.

20. In a window construction, a frame member comprising in cross section a base having a dovetailed groove in the exposed face thereof and having a flange extending from the edge of said base towards the inside of the window, in combination with an adapter member of channel shape comprising a base having a flange near the outside of the window extending outwardly from said base in a plane parallel with the plane of the window, said flange having a formation at the outer edge thereof adapted to engage the outer wall of said dovetailed groove in the frame member, said adapter base also having a flange extending from the edge thereof nearest the inside of the window outwardly in a plane parallel to the plane of the window and having a formation at the outer edge thereof adapted to engage the inner edge of the flange at the inner edge of the base of said frame member, said adapter member having a glass projection thereon.

21. In a window construction, a frame composed of members comprising in cross section a base having an inwardly extending flange projecting in a plane parallel with the plane of the window from the edge of said base towards the inside of the window, said flange adapted to constitute a glass receiving seat when the frame is utilized to hold a fixed pane of glass, and a supplemental member adapted to be fixed to the exposed face of said base near the edge of the base towards the outside of the window, said supplemental member including a flange extending inwardly in a plane parallel to the plane of the window, said flange being located towards the outside of the window and being substantially wider than the flange on the base near the inside of the window.

22. In a window construction, a frame composed of members comprising in cross section a base having an inwardly extending flange projecting in a plane parallel with the plane of the

- window from the edge of said base towards the inside of the window, said flange adapted to constitute a glass receiving seat when the frame is utilized to hold a fixed pane of glass, and a supplemental member adapted to be fixed to the exposed face of said base near the edge of the base towards the outside of the window, said supplemental member including a flange extending inwardly in a plane parallel to the plane of the window, said flange being located towards the outside of the window and being substantially wider than the flange on the base near the inside of the window, said supplemental member having a weather strip pocket therein.
- 5 23. In a window construction, a swinging sash comprising members formed of thin metal of substantially right angle triangular shape, one side of the triangle constituting a glass receiving seat and being provided with an inwardly projecting flange parallel with the plane of the window forming a glass receiving ledge, the diagonal side of the triangle having a longitudinal projection substantially midway of the width thereof for engagement with a weather strip.
- 10 24. In a window construction, a swinging sash comprising a rigid L-shaped extruded member, and a hollow member of relatively light metal enclosed and fitted on the L-shaped member, said hollow member being substantially of right triangular cross-section, one side of the triangle constituting a glass receiving seat and being provided with an inwardly projecting flange parallel with the plane of the window for forming a glass receiving ledge, and the oblique side of the triangle being formed to provide a longitudinally extending edge substantially midway of the width of said side for engagement with a weather strip.
- 15 25. In a window construction, a swinging sash comprising a rigid, hollow extruded member substantially of right triangular cross-section, one side of the triangle constituting a glass receiving seat and being provided with an inwardly projecting flange parallel with the plane of the window to form a glass receiving ledge, and the oblique side of the triangle being formed to provide a longitudinally extending flange, the outer extremity of the flange being angular in cross- 20 section and terminating in a lip which extends substantially at right angles to the plane of the window to have its edge directly engage and compress the sealing member as the sash is swung to closed position.
